J. S. McKAYE AND H. G. McKAY, OF NEW YORK, N. Y.

Design No. 2,748, dated August 13, 1867.

DESIGN FOR A STATUETTE.

The Schedule referred to in these Letters Patent and making part of the same.

TO WHOM IT MAY CONCERN:

Be it known that we, J. S. McKAYE and H. G. McKAY, of the city, county, and State of New York, have originated and designed a Statuette of Hon. Horace Greeley, editor of the New York Daily Tribune; and we hereby declare that the same is set forth in the following specification, being clearly shown in the photograph forming part of the same, and consists of a pedestal, A, of flat, circular form and suitable size, upon the top of which stands the figure, in full length, of Hon. Horace Greeley, in a position with the head B turned slightly to one side, and with the hands C clasped together in front, carrying under the left arm D a bundle of papers E. The overcoat F is not buttoned, and hangs loosely about him, and has two large side pockets G, with fly-covers H.

Claim.

The design for a statuette, substantially as described and shown.

The above specification of our invention signed by us this 6th day of July, 1867.

J. S. McKAYE,
H. G. McKAY.
